US00D935278S

(12) **United States Design Patent** (10) Patent No.: US D935,278 S
Hunter et al. (45) Date of Patent: ** Nov. 9, 2021

(54)	CUP	2,128,466 A	8/1938	Machotka
(71)	Applicant: YETI Coolers, LLC , Austin, TX (US)	2,215,402 A	9/1940	McDonald
(72)	Inventors: Desiree Hunter , Austin, TX (US); Liza Morris , Austin, TX (US); Roy Joseph Seiders , Austin, TX (US); Mark Carlson Rane , St. George, UT (US)	2,215,691 A	9/1940	East
		2,378,867 A	6/1945	Reichart
		2,414,697 A	1/1947	Pettersson
		2,484,608 A	10/1949	Cheyney
		2,610,489 A	9/1952	Clemensen
		2,675,954 A	4/1954	Vogel
		D177,559 S	5/1956	Emmert
		2,871,051 A	1/1959	Nesslein et al.
		D186,555 S	11/1959	Hunt
		2,928,570 A	3/1960	Fitch
		2,981,562 A	4/1961	Long
		3,118,560 A	1/1964	Cornelius
		3,128,029 A	4/1964	Price
		3,202,309 A	8/1965	Simpson
		3,206,210 A	9/1965	Bard
		3,261,633 A	7/1966	Sakuta
		3,342,370 A	9/1967	Johnson
		D209,308 S	11/1967	Schilling
		3,353,729 A	11/1967	Hull
		D209,533 S	12/1967	Cole
		D211,818 S	7/1968	Massey
		3,421,681 A	1/1969	Frank
		3,458,164 A	7/1969	Massey
		3,463,140 A	8/1969	Rollar
		D217,781 S	6/1970	Stone
		3,571,940 A	3/1971	Bender
		3,578,524 A	5/1971	Ignell
		3,602,386 A	8/1971	Brime
		3,603,100 A	9/1971	Ryan et al.
		3,679,253 A	7/1972	Simms
		3,682,352 A	8/1972	Doucette
		3,703,255 A	11/1972	Wade
		3,730,383 A	5/1973	Dunn et al.
		D227,532 S	7/1973	Refsgaard
		3,753,512 A	8/1973	Curry
		3,755,030 A	8/1973	Doman et al.
		3,765,559 A	10/1973	Sauvey et al.
		D229,006 S	11/1973	Sauvey
		D231,068 S	4/1974	Douglas
		3,827,925 A	8/1974	Douglas
		3,971,471 A *	7/1976	Ludder .....
				B65D 1/265

CLAIM

The ornamental design for a cup, as shown and described.

DESCRIPTION

The file of this patent contains at least one drawing executed in color. Copies of this patent with color drawings will be provided by the Office upon request and payment.

FIG. 1 is a top, front, left perspective view of a cup showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view at 8-8 in FIG. 6 thereof;

FIG. 9 is a top, front, left perspective view of a first alternative claimed configuration of a cup showing our new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is a cross-sectional view at 16-16 in FIG. 14 thereof;

FIG. 17 is a top, front, left perspective view of a second alternative claimed configuration of a cup showing our new design;

FIG. 18 is a front view thereof;

FIG. 19 is a rear view thereof;

FIG. 20 is a right side view thereof;

FIG. 21 is a left side view thereof;

FIG. 22 is a top view thereof;

FIG. 23 is a bottom view thereof;

FIG. 24 is a cross-sectional view at 24-24 in FIG. 22 thereof;

FIG. 25 is a top, front, left perspective view of a third alternative claimed configuration of a cup showing our new design;

FIG. 26 is a front view thereof;

FIG. 27 is a rear view thereof;

FIG. 28 is a right side view thereof;

FIG. 29 is a left side view thereof;

FIG. 30 is a top view thereof;

FIG. 31 is a bottom view thereof;

FIG. 32 is a cross-sectional view at 32-32 in FIG. 30 thereof;

FIG. 33 is a top, front, left perspective view of a fourth alternative claimed configuration of a cup showing our new design;

FIG. 34 is a front view thereof;

FIG. 35 is a rear view thereof;

FIG. 36 is a right side view thereof;

FIG. 37 is a left side view thereof;

FIG. 38 is a top view thereof;

FIG. 39 is a bottom view thereof;

FIG. 40 is a cross-sectional view at 40-40 in FIG. 38 thereof;

FIG. 41 is a top, front, left perspective view of a fifth alternative claimed configuration of a cup showing our new design;

FIG. 42 is a front view thereof;

FIG. 43 is a rear view thereof;

FIG. 44 is a right side view thereof;

FIG. 45 is a left side view thereof;

FIG. 46 is a top view thereof;

FIG. 47 is a bottom view thereof; and,

FIG. 48 is a cross-sectional view at 48-48 in FIG. 46 thereof.

The broken lines depicting the remainder of the cup show features that form no part of the claimed design. The contrast in shading shown in FIGS. 1-8 represents a contrast in appearance only and does not represent any particular color, material, texture or finish.
